OF LINCOLN, ENGLAND, ASSIGNORS TO RUSTON AND HORNSBY, LIMITED, OF LIN-
COLN, ENGLAND.

REVERSING MECHANISM FOR INTERNAL-COMBUSTION ENGINES.

1,327,995.

Specification of Letters Patent. Patented Jan. 13, 1920.

Application filed September 27, 1919. Serial No. 326,938.

To all whom it may concern:

Be it known that we, GEORGE WILFRID ACLAND GREEN, OSWALD WANS, and FREDERICK HOWARD LIVENS, subjects of the King of Great Britain, residing at Sheaf Iron Works, Waterside South, Lincoln, England, have invented new and useful Improvements in Reversing Mechanisms for Internal-Combustion Engines, of which the following is a

specification.

This invention relates to reversing mechanism for internal combustion engines having two or more cylinders which work on a two-stroke cycle and into which liquid fuel is injected by a pump at or near the end of the compression stroke during normal forward and backward running and at or near the beginning of the compression stroke for reversing the direction of running.

According to this invention a fuel injection pump is actuated by an inertia tappet and an eccentric on the shaft of the engine, and the stroke of the pump is reversed in relation to the reciprocations of the eccentric rod by altering the path of a joint pin between the eccentric and the tappet. The tappet may be actuated by a link connected to one end of a toggle lever whose other end is anchored to a fixed fulcrum, and the central pin of the toggle lever is connected to an eccentric on a shaft of the engine and the free end of the toggle lever is connected to means for altering its position, thereby reversing the engine.

The movements of the tappets may be controlled by springs whose tension is altered in order to vary the speed at which the tappet will come into engagement with the pump plunger, and also by guide plates which prevent the tappets from actuating the pump when it is so desired.

The reversal of the engine is effected by a single stroke longer than the normal stroke.

The annexed drawings illustrate reversing gear made in accordance with this invention. Figure 1 is an elevation drawn to a smaller scale, and Fig. 2 a plan of the toggle arrangement applied to an engine whose cylinders are arranged in pairs. Fig. 1^a shows some of the parts seen in Fig. 1 in the position for reverse running. Fig. 3 shows a clutch upon the driving shaft, Fig. 4 is a plan and Fig. 5 a sectional elevation of the

tappet controlling gear. Fig. 6 is a part left hand elevation of Fig. 1, Fig. 7 shows a modified form of the reversing handle, Fig. 8 illustrates diagrammatically in full lines the positions of the parts for normal forward and backward running when the plunger of the fuel pump reaches the end of its delivery stroke, and in dotted lines the positions of the parts when the crank shaft has turned through 180°, and Fig. 9 illustrates in full lines the positions of the parts for obtaining reversal in the direction of running, the full lines showing the parts when the fuel pump reaches the end of its delivery stroke, and the dotted lines the positions that these parts would take up after 180° further motion of the crank shaft.

In order that the mechanism may be more readily understood we will first describe the diagram Figs. 8 and 9. An inertia tappet *a* which is reciprocated over a shouldered guide plate *b* engages with and actuates the fuel pump plunger. This tappet is pivotally supported at the rear end upon a rocking link *c* pivoted at *d* to a fixed support and is connected to an actuating link *e* pivoted to the free end of a toggle lever *f* which is mounted at the other end to rock about the fixed pivot *g*, while the center pin *h* of the toggle lever is connected to a rod *i* driven from an eccentric *j* on a shaft driven by the engine. The free end *k* of the toggle lever is compelled to move in an arc by supporting it upon a rod *l* pivotally mounted upon a partially rotatable crank arm *m* which permits the pivotal connection of the rod *l* with the crank arm to be moved through a predetermined angle from the position shown in Fig. 8 to that shown in Fig. 9 at the will of the operator.

The arrangement of the parts is such that the tappet *a* travels farther to the right when the gear is in the position for reversing than when it is in the position for normal running forward and backward, thus giving a longer stroke to the fuel pump plunger. This is effected by so proportioning the crank *m* and the angle through which it is turned that the path of the point *k* in the "reverse" position is no longer approximately parallel to a line 1-1 passing through the central point of the path of the pin *h* and at right angles thereto, but lies

obliquely to it, the greatest distance of the point *k* from the line 1—1 being further than in the normal position of the crank *m* for forward and backward running.

5 Turning now to Figs. 1, etc., a single fuel pump 1 is provided for each cylinder and the pumps are mounted upon a bracket 2 bolted to the engine casting.

The plunger of each pump is actuated by 10 an inertia tappet *a* which is reciprocated upon a shouldered guide plate *b* mounted upon an arm 3 adjustably mounted on the bracket 2. The rear end of the tappet *a* is pivotally connected to one end of two 15 parallel links *e* and also to links *c* pivoted at *d*. The rear extremity of each link *e* is pivoted to the ends of the rear members 6 of toggle levers *f* whose front members 7 are mounted upon a fixed pivot *g*. The joints *h* 20 of the toggle levers *f* are pivoted to a common connecting rod *i* rigid with the strap of the usual eccentric for giving motion to the fuel pump plunger.

The ends *k* of the members 6 are supported 25 by a rod *l* pivotally mounted on a crank disk *m* mounted so as to be revolved a predetermined degree at the will of the operator through a hand lever 4 extending radially from the crank disk. By rotating the hand 30 lever 4 in the direction of the arrow 5 (see Fig. 1) the free ends *k* are lowered to cause the rear members 6 to take up a different angular position with respect to the operating rod of the eccentric, whereby reversal 35 is effected, the rear members 6 being partially rotated about the joint but the position of the forward members 7 with respect to the engine crank is not changed.

In order that the gear described above may 40 be mechanically returned to the normal position upon reversal in the direction of running of the engine the following mechanism may be employed:

The crank *m* is held temporarily in the reverse position by a pawl 8 pivoted to the bracket 2 at 9 and engaging a recess 10 in a cam 11 on the crank *m*. When the parts are in the position for normal forward and backward running the pawl bears upon a raised portion 12 of the cam. The pawl 8 is coupled by a rod 13 to a friction clutch 14 (see Fig. 3) mounted on the crank shaft of the engine. In normal running forward and backward the clutch is held out of engagement with the crank shaft by a rod 13, the pawl 8 resting on the raised part 12 of the cam 11. To reverse the engine the crank *m* is rotated and thereby the raised part of the cam is moved from engagement with the 55 pawl which moves downward and allows the clutch 14 to engage the crank shaft which tends to drag it around in the direction of its own motion. Further rotation of the crank *m* by the operator brings the recess 10 60 in the cam opposite the pawl 8 and allows

the rotation of the clutch 14 to draw the pawl into engagement with the recess and thus lock the crank *m* in the position to cause reversal of the engine. On reversal 70 of the direction of motion of the crank shaft by the injection of a charge of fuel at or near the beginning of the compression stroke, the clutch 14 moves back with the shaft toward its normal position. In so doing it 75 disengages the pawl from its recess and allows the crank *m* to fly back under the action of a spring 16 to its normal position. The raised portion of the cam then engages the pawl, thereby disengaging the friction clutch 14 from the crank shaft.

In order to control the quantity of fuel injected into the cylinder the crank *m* is mounted in an eccentric bearing 17. By rotating the eccentric bearing by a hand lever 18 the stroke of the inertia tappet and consequently the pump plunger are lengthened or shortened as desired.

For adjusting the speed of an engine having the cylinders arranged in pairs and employing one of the above gears for each cylinder (see Figs. 4, 5 and 6) a solid shaft 19 is arranged co-axially within a hollow shaft 20. On the solid shaft 19 are cams 21 formed by cutting away the shaft at each end at points in proximity to the guide plates *b* 90 for the inertia tappets *a*. Under each cam 21 bears one arm 22 of a two armed lever fulcrumed on the shaft 22*, the other arm 23 carrying a spring 24 (see Fig. 5) which is connected to the tappet *a*. To maintain the 100 two armed lever in contact with the shaft 19 an opposing spring 25 which is stronger than the spring 24 is anchored to the opposite side of the arm 23. By imparting to the solid shaft 19 a partial rotation either manually 105 by a hand lever 26 or mechanically by a pulley 27 which carries a strap operatively connected with the mechanism for disengaging the main engine clutch, the tension of the springs is altered so that both tappets will 110 engage their respective plungers only at a lower speed than that for normal forward running.

The hollow shaft 20 which is brought into play only at the time of reversal has upon 115 it cams 28 and 29. One of these cams 28 engages the head of a bolt 30 extending below one of the plates *b*, the bolt 30 being adjustably screwed into the plate *b* and locked by a nut 31. The other cam 29, 120 which is adapted to operate in conjunction with the other guide plate *b*, bears upon an arm 32 of one of the above mentioned two armed levers, and an arm 33 extending radially from the hollow shaft 20 is connected 125 by a link 34 to a forward extension 35 of one of the links *e* actuating the two inertia tappets *a*.

When the reversing lever is pulled over 130 during the motion of the engine, the hollow

shaft is partially rotated through the radially extending arm 33, causing the cam 29 engaging the arm 32 to partially rotate the latter about the shaft 22^x and so to reduce 5 the tension of the inertia tappet control spring 24 without altering the position of its respective guide plate. Meanwhile the cam 28 at the other end of the hollow shaft raises the other guide plate *b* about its 10 pivot, preventing engagement between its respective tappet and pump plunger so that only one of the two cylinders is used for changing the direction of rotation of the engine.

15 Fig. 7 shows an alternative gear for causing reversal. In this arrangement the disk *m* connected by a pin 36 to the link *l* which controls the toggle, is arranged as before. A hand lever 4 of angular form is mounted 20 on a fixed pivot at 37 and a pawl 38 is pivoted to it at 39. An arm 40 of the pawl is secured to the rod 13 connected to the friction clutch 14 on the crank shaft as before. The pawl 38 engages the pin 36 causing a 25 cam surface 41 on the forward end of the pawl 38 to keep the clutch 14 disengaged during forward or backward running. Assuming the engine to be running either forwardly or backwardly, the link *l* and pawl 30 38 occupy the position shown in full lines and the clutch 14 is held out of engagement, and the hand lever 4 is in the position shown in full lines. When it is desired to reverse the engine the hand lever is moved upwardly into the position indicated in dot 35 and dash lines, and the cam 41 of the pawl 38 rides over the pin 36 during this movement still keeping the clutch 14 disengaged until the pawl 38 engages with the pin 36, 40 the clutch 14 still remaining disengaged. The hand lever 4 is then moved downwardly again until the position of the pawl 38, shown in dotted lines, is reached, when the catch 42 upon the hand lever 4 engages a 45 fixed stop 43, preventing the hand lever from returning to the upper position under the action of the spring of the disk *m*. Just before this position is reached, however, the clutch becomes engaged and holds 50 the pawl 38 in contact with the pin 36. During this operation it will be noted that the pin 36 has been removed from the position shown in full lines to that shown in dotted lines, thereby obtaining reversal of 55 the engine.

When the engine has changed its direction of rotation the clutch on the crank shaft becomes operative in the reverse direction, and causes the pawl 38 to be lifted far 60 enough to allow the pin 36 to become disengaged but not so far as shown in full lines. The disk *m* returns to normal position under the action of its spring and the hand lever 4 remains in the position shown 65 in full lines. As the pin 36 returns to nor-

mal position it engages the cam 41 and moves the pawl 38 into the position shown in full lines, thus disengaging the clutch.

A pin 44 on the hand lever 4 prevents the catch 42 from falling too far when the hand lever is moved into the upper position, and when the engine is running in either the forward or backward direction the hand lever 4 is retained in the position shown in full lines by a fixed stop such as 45. 75

In order that it may be possible to cut out any pump that may be desired, we pivot at 46 above each pump a latch 47 having a hook 48 adapted to engage the outer end of the plunger 49 of the pump and prevent it from 80 movement out of the pump. The latch is provided with a screw 50 by means of which the latch may be screwed in its inoperative or operative position. When the latch is inoperative the screw rests beneath a fixed 85 stop 51 but when it is desired to put a pump out of action the screw is withdrawn so that its end can pass the stop. The latch is then turned on its pivot so that its hook 48 engages the front of the plunger 49 and the 90 screw is then screwed in again so that its end rests upon the upper surface of the stop 51.

What we claim is:—

1. In a two-stroke internal combustion engine, a fuel injection pump, an inertia tappet actuating the pump, an eccentric actuating the inertia tappet, a connection between the eccentric and the inertia tappet, a joint in the connection, means for altering 95 the path of the joint pin, and means for actuating the eccentric. 100

2. In a two-stroke internal combustion engine, a fuel injection pump having a plunger whose travel when the engine is reversed is longer than the normal, an inertia tappet actuating the plunger, an eccentric actuating the inertia tappet, a connection between the eccentric and the inertia tappet, a joint in the connection, means for altering the 110 path of the joint pin and means for actuating the eccentric. 105

3. In a two-stroke internal combustion engine, a fuel injection pump, an inertia tappet actuating the pump, an eccentric 115 actuating the inertia tappet, a connection between the eccentric and the inertia tappet, a joint in the connection, means for altering the path of the joint pin, means for causing the joint pin to return to its normal position after the reversal of the engine, and means for actuating the eccentric. 120

4. In a two-stroke internal combustion engine, a fuel injection pump having a plunger whose travel when the engine is reversed 125 is longer than the normal, an inertia tappet actuating the plunger, an eccentric actuating the inertia tappet, a connection between the eccentric and the inertia tappet, a joint in the connection, means for altering the 130

- path of the joint pin, means for causing the joint pin to return to its normal position after the reversal of the engine, and means for actuating the eccentric.
5. In a two-stroke internal combustion engine, a fuel injection pump, a toggle lever one end of which is anchored to a fixed fulcrum and the other connected to the tappet, a joint pin forming part of the toggle lever and connected to an eccentric, means for altering the path of the joint pin and means for actuating the eccentric.
6. In a two-stroke internal combustion engine, a fuel injection pump having a plunger whose travel when the engine is reversed is longer than the normal, an inertia tappet actuating the plunger, a toggle lever one end of which is anchored to a fixed fulcrum and the other connected to the tappet, a joint pin forming part of the toggle lever and connected to an eccentric, means for altering the path of the joint pin and means for actuating the eccentric.
7. In a two-stroke internal combustion engine, a fuel injection pump, an inertia tappet actuating the pump, an eccentric actuating the inertia tappet, a connection between the eccentric and the inertia tappet, a joint in the connection, means for altering the path of the joint pin, springs controlling the movement of the tappet, and means for actuating the eccentric.
8. In a two-stroke internal combustion engine, a fuel injection pump, an inertia tappet actuating the pump, an eccentric actuating the inertia tappet, a connection between the eccentric and the inertia tappet, a joint in the connection, means for altering the path of the joint pin, springs controlling the movement of the tappet, means for altering the tension of the springs, and means for actuating the eccentric.
9. In a two-stroke internal combustion engine, a fuel injection pump having a plunger whose travel when the engine is reversed is longer than the normal, an inertia tappet actuating the plunger, an eccentric actuating the inertia tappet, a connection between the eccentric and the inertia tappet, a joint in the connection, means for altering the path of the joint pin, springs controlling the movement of the tappet, and means for actuating the eccentric.
10. In a two-stroke internal combustion engine, a fuel injection pump having a plunger whose travel when the engine is reversed is longer than the normal, an inertia tappet actuating the plunger, an eccentric actuating the inertia tappet, a connection between the eccentric and the inertia tappet, a joint in the connection, means for altering the path of the joint pin, springs controlling the movement of the tappet, means for altering the tension of the springs, and means for actuating the eccentric.
11. In a two-stroke internal combustion engine, a fuel injection pump, an inertia tappet actuating the pump, a toggle lever, one end of which is anchored to a fixed fulcrum and the other connected to the tappet, a joint pin forming part of the toggle lever, and connected to an eccentric, means for altering the path of the joint pin, springs controlling the movement of the tappet and means for actuating the eccentric.
12. In a two-stroke internal combustion engine, a fuel injection pump, an inertia tappet actuating the pump, a toggle lever one end of which is anchored to a fixed fulcrum and the other connected to the tappet, a joint pin forming part of the toggle lever, and connected to an eccentric, means for altering the path of the joint pin, springs controlling the movement of the tappet, means for altering the tension of the springs, and means for actuating the eccentric.
13. In a two-stroke internal combustion engine, a fuel injection pump, an inertia tappet actuating the pump, a toggle lever one end of which is anchored to a fixed fulcrum and the other connected to the tappet, a joint pin forming part of the toggle lever and connected to an eccentric, means for causing the joint pin to return to its normal position after the reversal of the engine and means for actuating the eccentric.
14. In a two-stroke internal combustion engine, a fuel injection pump, an inertia tappet actuating the pump, an eccentric actuating the inertia tappet, a connection between the eccentric and the inertia tappet, a joint in the connection, means for altering the path of the joint pin, springs controlling the movement of the tappet, a lever connected to the springs, a cam engaging the lever, means for actuating the cam, and means for actuating the eccentric.
15. In a two-stroke internal combustion engine, a fuel injection pump having a plunger whose travel when the engine is reversed is longer than the normal, an inertia tappet actuating the plunger, an eccentric actuating the inertia tappet, a connection between the eccentric and the inertia tappet, a joint in the connection, means for altering the path of the joint pin, springs controlling the movement of the tappet, a lever connected to the springs, a cam engaging the lever, means for actuating the cam and means for actuating the eccentric.
16. In a two-stroke internal combustion engine, a fuel injection pump, an inertia tappet actuating the pump, a toggle lever one end of which is anchored to a fixed fulcrum and the other connected to the tappet, a joint pin forming part of the toggle lever, and connected to an eccentric, means for altering the path of the joint pin, springs controlling the movement of the tappet, a lever connected to the springs, a cam engaging the

- lever, means for actuating the cam and means for actuating the eccentric.
17. In a two-stroke internal combustion engine having its cylinders arranged in 5 pairs, fuel injection pumps, inertia tappets actuating the pumps, an eccentric actuating the inertia tappets, connections between the eccentric and the inertia tappets, joints in the connections, means for altering the path 10 of the joint pins, springs and guide plates adapted to control the movement of the tappets, means for altering the tension of the springs, and means for altering the position of a guide plate.
18. In a two-stroke internal combustion engine, having its cylinders arranged in 15 pairs, fuel injection pumps, inertia tappets actuating the pumps, toggle levers connected to the tappets, joint pins forming part of the 20 toggle levers and connected to an eccentric, springs and guide plates adapted to control the movement of the tappets, means for altering the tension of the springs, means for altering the position of the guide plates and 25 means for actuating the eccentric.
19. In a two-stroke internal combustion engine having its cylinders arranged in pairs, fuel injection pumps, inertia tappets actuating the pumps, toggle levers connected 30 to the tappets, joint pins forming part of the toggle levers and connected to an eccentric, springs and guide plates adapted to control the movement of the tappets, two coaxial shafts one carrying cams engaging levers 35 connected to the springs and the other a cam operating one of the aforesaid levers, a cam adapted to adjust one of the guide plates and means for actuating the eccentric.
20. In a two-stroke internal combustion engine, a fuel injection pump, a toggle lever 40 one end of which is anchored to a fixed fulcrum and the other connected to the tappet, a joint pin forming part of the toggle lever and connected to an eccentric, the free end of the toggle lever being connected to a device 45 for moving the pin from the position for normal running to that of reversing, means for holding the pin in reversing position and a friction clutch adapted to maintain the pin in the reversing position and to release 50 the pin upon the reversal of the engine, and means for actuating the eccentric.
21. In a two-stroke internal combustion engine, a fuel injection pump having a plunger whose travel when the engine is reversed 55 is longer than the normal, an inertia tappet actuating the plunger, a toggle lever one end of which is anchored to a fixed fulcrum and the other connected to the tappet, a joint pin forming part of the toggle lever and connected to an eccentric, the free end of the 60 toggle lever being connected to a device for moving the pin from the position for normal running to that of reversing, means for holding the pin in reversing position and a friction clutch adapted to maintain the pin in 65 the reversing position and to release the pin upon the reversal of the engine, and means for actuating the eccentric.

In testimony that we claim the foregoing 70 as our invention we have signed our names this 9th day of September, 1919.
